FRACTIONATING COLUMN.

Application filed January 31, 1925. Serial No. 6,152.

The present invention relates to improvements in fractionating columns, and will be fully understood from the following description thereof, illustrated by the accompanying drawings, in which:

Figure 1 is a side elevation of a portion of a column or tower embodying the present invention;

Figs. 2 and 3 are diagrammatic sectional views showing the relative placing of the parts of successive plates within the tower;

Fig. 4 is a sectional view on the line 4—4 of Fig. 5;

Fig. 5 is a vertical sectional view on the line 5—5 of Fig. 4;

Fig. 6 is a sectional view on the line 6 of Fig. 1, showing the construction of the higher plates of the column;

Fig. 7 is a detail vertical sectional view on the line 7 of Fig. 6; and

Fig. 8 is a vertical sectional view on the broken line 8—8 of Fig. 6.

Referring more particularly to the drawings, in Fig. 1 is shown a portion of the vertical cylindrical shell 10 of a fractionating tower embodying the present invention. This shell is provided with manholes 11 arranged in vertical rows, alternate manholes being set at an angle to one another for the purpose hereinafter set forth. As will be pointed out, these manholes are preferably of a size such that the sections forming the plates of the column may be inserted therethrough.

Typical plates of the column are shown in Figs. 4, 5 and 6. The type of plate illustrated in Fig. 6 differs from those illustrated in Figs. 4 and 5 principally in that, in the former, fewer overflows for reflux are provided, these plates being intended for use in portions of the column where less overflow liquid is anticipated.

As will be seen from Figs. 5 and 7, at suitable vertical intervals within the tower the circular flanges 12 are secured to its inner walls, and on these are mounted the sections forming the individual plates. The sections forming alternate plates are arranged at an angle to each other, preferably at substantially right angles. In the form illustrated, each plate is made up of four sections, the two inner sections being substantially mirror images of each other, and the two outer sections being likewise substantially mirror images of each other.

The center sections of the plates are designated by the numerals 13 and 13^a. These sections are formed at their sides with downwardly projecting flanges 14, cut away at their ends to permit the plate sections to rest on the supporting flanges 12. Suitable bolt holes are provided in the flanges 14, whereby the adjacent sections 13 and 13^a may be secured together, and at their outer margins secured to the adjacent plate sections. Each of the plate sections 13 and 13^a is provided with a number of upwardly projecting nipples 15, preferably of substantially rectangular shape. These projecting nipples provide for the passage of gas from the vapor space below the plate sections to that above it, and each of the nipples is provided with a substantially rectangular bubble-cap 16, the lower edge of which is suitably serrated as at 16^a. The nipples 15 and caps 16 may be so arranged as to provide a plurality of rows of bubble-caps substantially evenly spaced from one another, the rows extending substantially transversely across the plate sections. At their ends the plate sections 13 and 13^a are formed with upwardly projecting dams 17 and 17^a, so arranged that when the sections are properly placed, a pool 18 is formed, the wall thereof formed by dams 17 and 17^a substantially paralleling the rows of bubble-caps 16, these dams being formed with raised side portions 17^b to guide the liquid and restrain its flow. One such pool 18 is formed at each end of the plate, and these pools receive the liquid reflux discharged from the next plate above, in the manner hereinafter set forth. The pools 18 suitably include an area extending the width of the center sections, from which pools the overflow from the next plate above is distributed between the bubble-caps.

On opposite sides of the assembled center sections 13 and 13^a are provided the segmental sections 20 and 20^a, which may likewise be substantially mirror images of each other. The plate sections 20 and 20^a are provided on the side forming the chord of the arc with downwardly depending flanges 21, by which connection may be made with the flanges 14 on the outer margins of the center plates. Openings are provided, preferably symmetrically disposed with respect to a median line transversely across the assembled plate, which openings 22 serve as seats for the over-

flow pipes 23. The overflow pipes 23 are preferably tapered, in the form illustrated being shown as hollow frusta of inverted cones. Near their upper ends they are provided with more steeply pitched tapered shoulders 24, these shoulders seating in the openings 22, which are bevelled to correspond to their width. The construction of these overflow pipes and their seating is most clearly illustrated in Fig. 7. If desired the plate sections 20 and 20^a may also be provided with bubble-caps 25, of the same type as the bubble-caps 16 or of generally similar type, likewise preferably arranged symmetrically with respect to a transverse median line through the assembled plates. These bubble-caps are so disposed with reference to the pools 18 as to baffle and subdivide the portion of the overflow streaming over the sides of the pools 18 into streams of substantially the same size as those formed by the bubble-caps 16. Deflectors 25^a may likewise be provided to aid in an even distribution of the overflow.

Around the outer margins of the sections 25, 20 and 20^a there are provided upwardly extending flanges or ribs 26, and at the outer ends of the sections 13 and 13^a, the upwardly extending flanges or ribs 27 are provided. These upwardly extending flanges together form a rim around the assembled plate, and in the center plate sections 13 and 13^a, they also form an outer wall for the pool of reflux held back by dams 17 and 17^a.

To aid in holding the bubble-caps in their proper positions, angular lugs 28 are secured to the upwardly extending flanges 26 of the plate sections 20 and 20^a, and straps 29, suitably of angle iron, are extended transversely across the tops of the assembled plates, these straps passing under the lugs 28. They are held in position by any suitable means, for example, the pins 30 passing through suitable openings in the lugs 28 and the ends of the straps 29.

The plate sections forming each plate of the column are suitably arranged at an angle of approximately 90° with respect to those above and below it. Thus, in Fig. 5, for example, three plates are illustrated. As clearly shown in that figure, the sections forming the center plate, designated B, lie at right angles to those of the upper and lower plates designated A and C respectively. As a result of this arrangement, the overflow pipes arranged in the plate sections 20 and 20^a of any selected plate, for example the plate C, extend into the pool 18 formed in the ends of the center sections 13 and 13^a of the next lower plate (plate B in the example illustrated). The nipples for the passage of vapors and the bubble-caps 16 and 25 of each assembled plate are preferably arranged to distribute substantially uniformly the overflow liquid passing over the dams 17 and 17^a forming the pools 18 at the ends of the center

plates. In the form illustrated, the bubble-caps 25 and deflectors 25^a baffle and similarly distribute the flow of overflow liquid from the sides of the pools 18. As a result of the arrangement of the bubble-caps the liquid is caused to travel in approximately uniform streams around and between the bubble-caps to the central portion of the plate, there joining the flowing to the oppositely disposed overflow pipes. This course is indicated on Fig. 4 of the drawings by arrows. The depth of the stream of overflow liquid is greater toward the center of the plate, and decreases toward the outer plates. In order to prevent channeling the center bubble-caps are raised by shims 16^a. The shims 16^b are inserted between the lower caps and straps 29.

The manholes 11 of the outer shell of the column or tower are sufficiently large to permit the insertion of the individual sections forming the plates of the tower. Figures 2 and 3 show diagrammatically the relative arrangement within the tower of successive plates, the parts shown diagrammatically being indicated by the same reference numerals as the corresponding parts in the more detailed drawings.

For convenience the invention has been described in connection with a tower of circular cross section, and with the plates made up of four sections. It is readily understood that the form of the tower and the number of sections of which the individual plates are formed may be varied as desired. The specific details of the form of construction set forth are not to be regarded as limitations upon the scope of the invention except as in so far as included in the accompanying claims.

We claim:

1. In a fractionating plate of the bubble type, dams at opposite ends of said plate forming pools for the reception of overflow liquid from higher plates, vapor uptakes and bubble-caps between said dams, said bubble-caps being substantially evenly spaced, and overflow means oppositely disposed on said plate on a median line between said dams.

2. In a fractionating plate of the bubble type, dams at opposite ends of said plate forming pools for the reception of overflow liquid from higher plates, overflow means disposed on a median line between said dams and vapor uptakes and bubble-caps on said plate on each side of said median line, said bubble-caps being disposed to divide into substantially equal streams the overflow liquid issuing from the pools formed by said dams.

3. In a fractionating plate of the bubble type, dams at opposite ends of said plate forming pools for the reception of overflow liquid from higher plates, overflow means disposed in symmetrical relation to a median line between said dams and vapor uptakes

- and substantially rectangular bubble-caps disposed on each side of said median line and spaced to substantially evenly subdivide the overflow liquid issuing from the pools 5 formed by said dams.
4. A fractionating tower provided internally with spaced supporting flanges, fractionating plates, each comprising a plurality of sections resting at their outer margins on 10 one of said annular flanges, each of said sections being provided adjacent the next section with downwardly depending flanges, and means for securing together the downwardly depending flanges of adjacent sections 15 of said plates.
5. A fractionating tower provided internally with vertically spaced annular flanges, fractionating plates each comprising a plurality of sections, resting at their outer margins on one of said annular flanges, each of 20 said sections being provided adjacent the next section with downwardly depending flanges, means for securing together the downwardly depending flanges of adjacent plate sections, 25 the tower being provided with openings near said plates for the insertion and removal of the plate sections.
6. A fractionating tower provided internally with spaced horizontal annular flanges, 30 fractionating plates of the bubble type, each having overflow openings at opposite ends thereof in fixed relation to a median line therethrough, a free passage between said oppositely arranged openings, a plurality of 35 elongated bubble-caps on either side of said free passage forming a plurality of liquid channels at right angles to said median line, adjacent plates being arranged with said median lines angularly disposed with reference to one another. 40
7. In a fractionating plate having an opening with steeply tapering sides, an overflow pipe extending through said opening, said overflow pipe being provided exteriorly with a projecting shoulder having tapered sides 45 adapted to seat within said opening. 45
8. A fractionating plate having an opening with steeply tapered sides, a conical, downwardly tapering, overflow pipe extending through said opening, said overflow pipe 50 being provided exteriorly near its top with an annular projecting shoulder having tapered sides adapted to seat within the opening in the plate. 50
9. In a fractionating plate, means for 55 maintaining oppositely disposed pools on said plate for receiving overflow from plates above, vapor uptakes and bubble-caps arranged adjacent each pool maintaining means to guide the overflow from the pools to a central area and means for guiding the overflow from such central area to the plate below. 60
10. In a fractionating plate, means for maintaining oppositely disposed pools on said plate for receiving overflow from plates 65 above, vapor uptakes and equidistant rectangular bubble-caps arranged adjacent each pool maintaining means to guide the overflow in substantially equal streams to a central area, and overflows provided from such central 70 area to the plate below. 70
